[57] CLAIM

The ornamental design for cat litter box, substantially as shown and described.

DESCRIPTION

FIG. 1 is a perspective view of a cat litter box showing my new design;

FIG. 2 is a top plan view thereof;

FIG. 3 is a side elevational view thereof, the side opposite being substantially a mirror image;

FIG. 4 is a front elevational view thereof, the end opposite being substantially a mirror image;

FIG. 5 is a bottom plan view thereof;

FIG. 6 is a front perspective view of a modified form of the design shown in FIGS. 1-5;

FIG. 7 is a top plan view thereof;

FIG. 8 is a side elevational view thereof; and

FIG. 9 is a bottom plan view thereof.

The characteristic feature of my design resides in the configuration of the curving lip of the inner container which covers the edge of the basket member.
